UNITED STATES PATENT OFFICE

127,186

DESIGN FOR A NECKLACE OR THE LIKE

Benjamin L. Atkins, Miami, Fla.

Application April 3, 1941, Serial No. 109,121

Term of patent 7 years

To all whom it may concern:

Be it known that Benjamin L. Atkins, a citizen of the United States, residing at Miami, in the county of Dade and State of Florida, has invented a new, original, and ornamental Design for a Necklace or the like, of which the following is a specification, reference being had to the accompanying drawing, forming part thereof, wherein:

Figure 1 is a front elevational view of a necklace or the like, and

Figure 2 is a side elevational view of the same as seen from the left of Figure 1.

The dominant feature of the invention is shown in full lines on the drawing.

I claim:

The ornamental design for a necklace or the like, substantially as shown and described.

BENJAMIN L. ATKINS.
